(57) **CLAIM**

The ornamental design for an aircraft engine safety shield, as shown and described.

DESCRIPTION

FIG. 1 is a front elevation view of an aircraft engine safety shield showing my new design;

FIG. 2 is a rear elevation view thereof;

FIG. 3 is a right elevation view thereof, the opposite side being a mirror image of the shown; and,

FIG. 4 is an isometric view thereof.

The broken lines in the drawings depict environmental subject matter only and form no part of the claimed design.

1 Claim, 4 Drawing Sheets

FIG. 1

FIG. 2

FIG. 3
